UNITED STATES PATENT OFFICE.

ERNEST R. VIBERG, OF MONTREAL, QUEBEC, CANADA.

METAL WINDOW-SASH.

1,027,675.

Specification of Letters Patent. Patented May 28, 1912.

Application filed July 22, 1909. Serial No. 509,072.

To all whom it may concern:

Be it known that I, ERNEST R. VIBERG, of the city of Montreal, in the Province of Quebec and Dominion of Canada, have invented 5 certain new and useful Improvements in Metal Window-Sashes, of which the following is a full, clear, and exact description.

This invention relates to metal window sashes, and more particularly to sashes 10 adapted for use in railway cars.

The main object of the invention is to provide a sash frame of seamless metal tubing which will be very durable and efficient, and yet light in weight and 15 comparatively inexpensive.

The invention consists essentially of a window sash of metal bent into tubular form, with a flange at the glass or panel side combined with retaining strips or 20 clamping devices that hold the parts in position.

In the drawings which illustrate my invention:—Figure 1 is a partial elevation of a window constructed according to my invention. Fig. 2 is a cross sectional view on the line 5—6 of Fig. 1 showing one method of forming the corner. Fig. 3 is a similar view on the line 9—10 of Fig. 1, showing another method of forming the corner. Fig. 4 30 is a further cross-sectional view on the line 7—8 of Fig. 1.

In the above defined figures, 11 designates a plurality of seamless tubular sections of metal formed into a sash of any desired 35 contour. The sections are provided with inwardly projecting hollow flanges 12 against which the glass panel 13 is clamped through its peripheral setting 14 by the bead strip 15. The setting 14 may be of any suitable 40 resilient material, such as rubber, and the bead strip 15 of any desirable form such as that shown in the drawings. The tubular sections 11 may be united at the corners of the sash either by a miter or by a mortise 45 and tenon joint. In the former case, the sections after being brought together are riveted to a casting 16 which holds the corner rigid. In the latter case, the mortise is

the entire internal thickness of the section and the tenon is formed of a tubular member 17, of adequate thickness and strength, which is riveted to the rails and inserted in the side stiles and riveted there, as seen in the right hand corner of Fig. 1.

As the metal of which the sections are constructed is of necessity too thin to be threaded for the reception of the screws 18, which secure the bead strips 15, I provide a comparatively thick filler strip 19 threaded to receive the screws. The filler strip extends into the hollow flange 12, as seen in the drawings, and is secured there by depressing the inner wall of the flange into recesses formed in the abutting surface of the filler, as seen at 20, in Figs. 2 and 4. The filler is then turned under the panel seat and then downwardly at the required angle to bring the portion 21 thereof parallel with that portion of the bead strip 15 through which the screws 18 pass. Whenever it is desired to secure a handle, lock, or other fittings 22 to the sash, the filler is provided with a lug or extension 23, which is bent to lie against that wall of the sash to which the fitting is to be secured. The screws 24 for attaching the fitting pass through the wall of the sash and into the lug 23. If so desired, the tenon members 17 may be formed integral with the fillers in the rails, thus attaining additional rigidity and reducing the stress 80 on the thin walls of the rails. It will be seen that the screws 18 which pass through the bead strips 15, through the fillers 19, draw the sections 11, and through the fillers 19, draw the members together and hold same in spring 85 tension, thus locking the screws in position and at the same time maintaining all the parts in most efficient coöperation.

Having thus described my invention, what I claim is:—

1. A metallic sash for windows and the like comprising an approximately rectangular tubular section, a flange formed integral therewith, a filler strip, means for holding the filler strip and flange together, a bead strip, and means connecting the filler strip

with the bead strip to hold same in tension, substantially as described.

2. A metallic sash for windows and the like comprising a series of seamless tubular sections, flanges formed integral therewith, means for joining said sections, a filler strip, means for holding the filler strip and flanges together, a bead strip, and means

connecting the bead strip with the filler strip to maintain the parts in spring tension. 10

In witness whereof I have hereunto set my hand in the presence of two witnesses.

ERNEST R. VIBERG.
